UNITED STATES PATENT OFFICE.

GEORGE V. SHEFFIELD, OF SCHENECTADY, NEW YORK, ASSIGNOR TO HIMSELF
AND LEWIS SICKLER, OF SAME PLACE.

PRINTING-TELEGRAPH.

SPECIFICATION forming part of Letters Patent No. 394,302, dated December 11, 1888.

Application filed December 31, 1887. Serial No. 259,477. (No model.)

To all whom it may concern:

Be it known that I, GEORGE V. SHEFFIELD, of Schenectady, in the county of Schenectady and State of New York, have invented a new 5 and Improved Printing-Telegraph, of which the following is a specification, reference being had to the annexed drawings, forming a part thereof, in which—

Figure 1 is a diagrammatical view of my 10 improved printing-telegraph. Fig. 2 is a side elevation showing the general arrangement of the magnets, steam-cylinders, and whistle. Fig. 3 is a plan view of the apparatus for producing a single character or letter, showing 15 the connection therewith of the transmitting apparatus. Fig. 4 is a side elevation, partly in section, of the same; and Fig. 5 is a detail side elevation of the paper-feeding mechanism.

20 Similar letters of reference indicate corresponding parts in all the views.

The object of my invention is to construct a machine for transmitting messages telegraphically, so as to deliver the message in 25 the form of a printed strip or stencil.

The object of my invention is, also, to provide an attachment for making an audible signal for each letter printed, so that the message may be read by sound, if desired.

30 My invention consists in a transmitter formed of two rollers adapted to carry forward a perforated sheet of paper; a series of spring-actuated fingers held in contact with one of the rollers of the paper; a number of 35 line-wires corresponding to the number of fingers in the transmitter; a receiver consisting of a series of steam-cylinders arranged in a circle and connected with printing-levers; an electro-magnetic device connected with each 40 cylinder and with one of the line-wires, and a series of whistles connected with the steam-cylinders and adapted to be operated by the exhaust, all as hereinafter more fully described.

45 The transmitter mechanism consists of the rollers A B, journaled in the frame C, a roller, D, containing a perforated strip, *a*, of paper, representing the message, and a series of fingers, *b*, insulated from each other and resting upon the lower roller, B, or upon the pa-

per strip *a*, passing between the rollers A B. Each finger *b* is drawn down by a spring, *c*, so that when the paper passes through the rollers each finger *b* is made to drop onto the lower roller, B, wherever an opening in the 55 paper strip *a* occurs in the path of the said finger. The roller B is connected with one pole of the battery, the remaining pole of the battery being connected with the ground-wire *d*, and each finger *b* is connected with one of 60 the line-wires E, there being as many line-wires as there are characters in the code.

The receiving-instrument is composed of a series of devices which are approximately alike; therefore a description of one of them 65 will answer for all. In the center of the receiving-instrument is arranged an anvil, F, for receiving the impression of all the printing-levers G, as they are thrown down in the manner presently to be described, the printing-levers being arranged in a circle with the type or stamp representing the letter placed so as to strike in the center of the anvil with their tops all in one direction. Each printing-lever G is pivoted to a support, *e*, attached 70 to the base-piece H. To the same base-piece is secured a standard, *f*, which supports the steam-cylinder I, containing a piston, J. The rod *g*, attached to the piston J, is provided with a connecting-rod, *h*, which is pivoted to 75 the printing-lever G at a point above its fulcrum. In the bottom of the cylinder I are two ports, *i j*. In the top of the cylinder I is an opening, *k*, in which is inserted a plug-valve, *l*, adapted to close the port *j*. The 80 valve *l* is connected with the lever *m*, pivoted in an ear, *n*, at the top of the cylinder and extending rearwardly. To the free end of the lever *m* is attached a rod, *o*, carrying at its lower end a weight, *p*, and to the said lever *m*, at a point above the valve *l*, is secured 85 an armature, *q*.

To the head of the cylinder I is attached an arm, *r*, which extends upward with its extremity above the pivoted end of the lever *m*. 95 To the arm *r* is secured an electro-magnet, K, whose poles are located above the armature *q*. Each magnet K is connected with one of the line-wires E. The port *j* communicates by a pipe, *t*, with the steam-supply, and a 100

pipe, u , leading from the port i , is connected with a whistle, v , or, in lieu thereof, with any suitable sound-producing device. To the ear n at the top of the cylinder I is secured a rod, 5 a' , which extends forward and forms a guide for the spiral spring b' . To the printing-lever G is pivoted a rod, c' , provided with a stirrup, d' , having an apertured cross-bar, e' , adapted to slide upon the rod a' . The spring 10 b' abuts upon a post, f' , secured to the frame of the machine, and tends to raise the printing-lever G into a vertical position, and opposes the action of the steam upon the piston J in the cylinder I .

15 To the standard F' of the anvil F is fitted a flanged sleeve, L , in the flange of which are inserted rods g' , which extend through the base of the machine, and are surrounded by springs h' , which tend to draw the rods and 20 the sleeve downward. To the top of the standard F' of the anvil F is secured a table, M , having upon one side of the standard F' a slide, through which passes one arm, i' , of a plate, N , the other arm of which rests horizontally upon the table M . In the arm i' of the plate N is formed an oblique slot, y' , through which projects a stud, k' , from the sleeve L . The horizontal part of the L -shaped plate N carries a spur, l' , which is adapted 25 to engage the strips $m' n'$ of paper running over the table M . The said paper strips pass through a guide, o' , which compels them to move over the anvil F . The extremity of the guide o' is twisted and provided with a longitudinal slot, p' , as shown in Fig. 4.

30 To the support e is pivoted a lever, O , one end of which extends under the flange of the sleeve L , the opposite end being connected with the slotted plate q' , arranged under the piston-rod g . The slot of the plate q' is arranged obliquely, and to the piston-rod g is attached a slotted arm, r' , which embraces the plate q' and carries a pin, s' , which passes through the slot of the plate q' , and tends to 35 move the said plate up or down as it is carried outwardly or inwardly by the rod g .

The operation of my improved printing-telegraph is as follows: A strip of paper, a , which is perforated in any well-known way, so as to 40 represent the message, is placed upon the roller D and passed between the rollers $A B$, and as the roller A is made to revolve, by means of a crank placed upon its shaft, a current from the battery is sent in one direction 45 to the ground and in the other direction through the roller B , through the finger b , which is in contact with the said roller, through one of the perforations of the paper, through the line-wire E to the magnet K of the 50 di- tant receiving-instrument, and thence to the ground. The armature q is drawn upwardly, 55 opening the valve l , admitting steam to the cylinder I , which pushes the piston J forward, carrying the lever G over, bringing the type 60 or punch carried by the lever into contact with the paper strip m' and against the pressure of the spring b' , thus cutting in the pa-

per strip the stencil of the letter or character, the lower strip of paper, n' , serving as a backing for the upper strip, m' . When the piston J passes the port i , the steam contained by the cylinder I escapes through the pipe u to the whistle v , and as soon as the steam escapes the spring b' returns the lever G and the piston J to the point of starting, the valve l 70 having been closed when the main-line circuit was interrupted. The return of the piston J , by virtue of the engagement of the pin s' with the slot in the plate q' , raises the inner end of the lever O , thereby pushing up the sleeve 75 L and moving upward the pin k' in the slot j' of the plate N . The rising of the plate N brings the spur l' into engagement with the strips of paper $m' n'$, and the further upward movement of the sleeve L , by the engagement 80 of the pin k' with the oblique slot y' , causes the plate N and the paper strips $m' n'$ to move forward the width of one letter, and when the next aperture in order upon the paper strip a passes one of the fingers b another contact 85 is made, completing a circuit through another of the line-wires E and through another of the magnets K , thus producing another impression in the paper in the manner already described; also blowing another one of the 90 whistles v , thereby producing another sound of a different tone, representing the character or letter impressed or cut in the paper strip m' .

Having thus described my invention, I claim 100 as new and desire to secure by Letters Patent—

1. In a printing-telegraph receiving-instrument, the combination, with the printing mechanism, of a steam-actuated piston, a 105 steam-cylinder provided with supply and exhaust ports, and an electro-magnetic valve-controller, substantially as described.

2. In a printing-telegraph receiving-instrument, the combination, with a series of printing-levers carrying dies representing characters, a series of steam-cylinders provided with pistons connected with the printing-levers, one to each printing-lever, of a retractile spring for returning the printing-lever and 110 the piston to the point of starting, a valve adapted to admit steam to the cylinder, and an armature-lever and an electro-magnet for operating the valve, substantially as described. 115

3. In a steam-actuated receiving-instrument for printing-telegraphs, the combination, with the piston and piston-rod of the steam-cylinder, of a feed-lever adapted to be 120 operated by the movement of the piston-rod, and paper-feeding mechanism arranged to be worked by the feed-lever, substantially as described.

4. In a printing-telegraph, the combination of the steam-cylinder I , provided with the ports $i j$, the valve l , adapted to close the port j , the armature q , connected with the valve l , the electro-magnet K , arranged to act 125 upon the armature q , the piston J , the pis-

ton-rod *g*, the connecting-rod *h*, the printing-lever *G*, the rod *c'*, provided with the stirrup *d'*, the spring *b'*, and the anvil *F*, for receiving the impressions of the printing-lever, substantially as described.

5. In a printing-telegraph, the combination of a steam-cylinder, *I*, provided with the ports *i*, *j*, the valve *l*, adapted to close the port *j*, the armature-lever *m*, carrying the weight *p*, the armature *q*, attached to the armature-lever *m*, the electro-magnet *K*, arranged to act upon the armature *q*, the piston *J*, fitted to the cylinder *I* and adapted to open and close the port *i*, the whistle *v*, connected with the port *i*, the piston-rod *g*, the printing-lever *G*, the feed-lever *O*, provided with the slotted plate *q'*, the arm *r'*, carrying the pin *s'*, engaging the slotted plate *q'*, the anvil *F*, the sliding spring-actuated sleeve *L*, provided 15 with the stud *h'*, the table *M*, the diagonally-

slotted plate *N*, carrying the point *l'*, and the paper-guide *o'*, substantially as described.

6. In a printing-telegraph system, the combination, with a series of steam-cylinders, *I*, provided with the steam-supply port *j* and 25 exhaust-port *i*, the valves *l*, armature-levers *m*, provided with the armatures *q*, and the electro-magnets *K*, adapted to act upon the armatures *q*, of the finger *b*, connected electrically with the magnets *K*, the conducting-roller *B*, connected electrically with the current-generator, a perforated strip of paper, *a*, adapted to make and break the connection between the fingers *b* and the roller *B*, and the line and local electrical connections, substantially as described. 30
